UNITED STATES PATENT OFFICE

GUY P. THURBER, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

SAFETY SIGNAL SYSTEM.

1,232,442.

Specification of Letters Patent.

Patented July 3, 1917.

Application filed November 1, 1911. - Serial No. 658,033.

To all whom it may concern:

Be it known that I, GUY P. THURBER, a citizen of the United States, residing at Pittsburgh, in the county of Allegheny and

5 State of Pennsylvania, have invented a new and useful Safety Signal System, of which the following is a specification.

The present invention relates to improvements in safety signal systems, and more particularly is a safety signal system especially adapted for use in connection with electric traction or interurban railroads provided with a single track intended for traffic in both directions, this particular system referring to the track or rail connections, and designed for use in connection with the cab or motor car mechanisms, as set forth in applicant's case filed April 16, 1911, Serial No. 555,804.

20 In this particular signal system, train controlling points are located along the track, and are each provided with a loop circuit controlled by a circuit breaker from a distant point, and when opened forms a means of automatically cutting off the power and setting the brakes upon the car or train, as well as giving signals to the car or train which passes over the insulated joints at either end of the blocks or signal points.

30 To produce a signal system adapted for safety upon this class of railroads, it is essential that when a car or train enters a block, that an approaching car or train in either direction, that is in front or in rear 35 of the car or train within the block, must be stopped or notified to avoid accidents, and to this end, this invention has been devised.

With the foregoing and other objects in view which will appear as the description 40 proceeds, the invention resides in the combination and arrangement of parts and in the details of construction hereinafter described and claimed, it being understood that changes in the precise embodiment of 45 the invention herein disclosed can be made within the scope of what is claimed without departing from the spirit of the invention.

In the drawings:-

50 Figure 1 is a diagrammatic view of station A of this signal system.

Fig. 2 is a similar view of station B.

Fig. 3 is a similar view of station C.

Fig. 4 is a diagrammatic representation of a grade crossing in the system, and

Fig. 5 is a view of station D, all of the 55 said stations forming a series of operably connected blocks and illustrating a complete safety signal system.

Referring to the drawings, and as shown therein, the track or railroad system is divided into stations A, B, C and D, respectively, which are located at sidings or passing points, and the full description of which will presently appear.

The instruments located at each station 65 will be and are substantially identical, so that a detail description of either one will be sufficient to cover the others, and such instruments are operated by power supplied to the track from two independent blocks, 70 which blocks are arranged one on each side of the respective station, as for instance, blocks A' and A², at station A; blocks B' and B², at station B; blocks C' and C², at station C; and blocks D' and D², at station D. 75

Like instruments and equipment in each block, as above set forth, are designated by the same reference characters, and the blocks are separated by the induction bonds 1, such for instance as between block A² and block 80 B', and the other induction bond 2, located at or near the siding A³, as indicated at station A.

By referring to station C, the power for controlling the signaling along the rails 4 85 and 5, in block C', is supplied to the track at the induction bond 1 by wires 102 and 103 from transformer 3, which takes the current from the line, at for instance 2200 volts, or some high potential, and transforms the 90 current to 10 or 11 volts, for the signal track circuit, which feeds through wires 102 and 103, into the rails 4 and 5, leading to the opposite end of the block at station C, where it flows by wires 104 and 105 to the track 95 relay 6, having one of its coils 6', energized by a separate transformer 7, through wires 106 and 107, at 110 volts.

The various circuits and instruments controlled by this relay 6, of block C', are as 100 follows, viz:-the circuit breaker 8, located at the siding C³, of station C, the line relay 9, through the repeating relay 25, in the adjacent block B², the circuit breaker 10 in block C² and with conditions favorable to 105 assist in controlling circuit breaker 11 at station C, the light signal indicators 12 and 13 also being operated.

The circuit closed to control the circuit breaker 8, is through armature 6^a, point 6'', wire 108, circuit breaker 8, wire 18', wire 109, wire 107, transformer 7, wire 106, wire 6^b to armature 6^a.

The circuit closed to control the repeating relay 25, is from transformer 7, wire 106, wire 6^b, armature 6^a, point 6^c, wire 25'', repeating relay 25, wire 25', wire 10 112, wire 111, wire 107 to the other side of the transformer. The energizing circuit for the line relay 9 is from the secondary of transformer 7 of station D, wire 106, wire 6^b, armature 6^a, point 6^c, wire 9'', relay 9 15 of station C, wire 9', wires 107 and 111 to the transformer 7 at station D.

The circuit breaker 10 shown in Fig. 4 is controlled through transformer 7 of station C, wire 107, wire 109, wire 10^a of Fig. 20 4, circuit breaker 10, wire 10', point 10'' of relay 9 at station C, armature 9^a, wire 10^b, wire 25'', point 6^c, armature 6^a, wire 6^b, wire 106 to the transformer 7.

The circuit breaker 11, is operated by a 25 circuit as follows:—transformer 7, wire 107, wire 109, wire 11', circuit breaker 11, wire 17', armature 9^b, point 9^c, wire 115, point 15'', armature 15^a, wire 116, wire 106 to the transformer 7.

The light signal indicator 12, is supplied 30 with current from the transformer 7, through wire 107, wire 109, wire 12', light signal indicator 12, wire 12'', point 6^c, armature 6^a, wire 116, point 16', armature 16^b, 35 wire 117, wire 106 to the transformer 7.

The light signal indicator 13, is supplied with current from the transformer 7, through wire 107, wire 109, wire 13', light signal indicator 13, wire 13'', reverse point 40 6^b, armature 6^a, wire 6^b, wire 106 to the transformer 7.

Referring to the line relay 9 in block B², the instruments controlled by this relay at station B, are as follows: circuit breakers 45 10 and 11, and light signal indicator 14''.

The circuits formed to operate the circuit breakers 11 and 10, are identical with those just described as pertaining to station C, but in this instance the light signal indicator 50 14, is operated from the transformer 7, wire 106, conductor 117, armature 9^a, point 9^c, wire 118', armature 15^a, point 15^b, wire 14'', signal indicator 14, wire 14', wire 109 and 55 wire 107 to the transformer 7.

In block C², it will be seen that the track rails 4 and 5, are electrified by the transformer 3 of Fig. 5, through wires 118 and 119, and control the track relay 15, through wires 120 and 121 in said block C², this 60 relay 15 in turn controlling the line relay 16 in block D', circuit breaker 17 in block C', circuit breaker 18 at the siding C³, and opening one side of the double circuit supplying current to control the circuit breaker 65 11 at station C, the light signal indicator 14

in block C² and light signal indicator 19 in block C', being operated simultaneously with the above instruments.

The line relay 16 of the block D', is supplied with current from the transformer 7, 70 through wire 107, wire 16', relay 16, wire 122, point 15^b, armature 15^c, of the relay 15 at station C, wire 116, wire 114, coil 15^k, wire 107, wire 9', relay 9, wire 9'', point 6^c, at station D, armature 6^a, wire 6^b, and wire 75 106 to the transformer 7.

The circuit breaker 17 in the block C', is supplied with current from the transformer 7, at station C, through the wire 107, wire 109, circuit breaker 17, wire 17', point 6^x, 80 armature 6^m, wire 122, point 15^b, armature 15^c, wire 116, and wire 106 to the transformer 7.

The circuit breaker 18, at the siding C³, is fed with current from the transformer 7, 85 by wires 107 and 109, wires 18', 110, circuit breaker 18, wire 18'', point 15^a, armature 15^c, wire 116, and wire 106 to the transformer 7.

And the circuit controlling the light signal indicator 14 in station C is similar to 90 that described in station B. The circuit which, however, controls the light signal indicator 19, is from the transformer 7, the wires 107, 109 and 19', the indicator 19, wire 95 19'', point 15^c, armature 15^a, wire 116, and wire 106 to the transformer 7.

The line relay 16 of block D', controls the circuit breaker 11, at station D, the circuit breaker 17 in block D', and the light signal 100 indicator 12 of block D', all of which have been described in operative relation in station C.

The loop circuit, comprising the wires 10^b and 10^c and armature 10^a, and which is connected around the insulated joint 20 of block C², is of sufficient carrying capacity 105 to supply current to operate controlling mechanism on the train or car, and this insulated joint is located directly opposite the 110 insulated joints 20, in the other rail. The two insulated joints 20 form a combination, which under proper conditions, breaks a local circuit in a train passing over said joints, and this point 20, is designated as a controlling 115 or stopping point in block C².

It will be seen that there are two other insulated joints 20'' and 20', mounted in the rails, one a sufficient distance away to permit a single truck of a car to stand in the 120 insulated section, and the other joint located a rail length from the signaling point, while around these insulated joints are installed non-inductive bonds 200 and 201, of sufficient carrying capacity to transmit the entire 125 return circuit of the propulsion or traffic current traversing the rails.

By the above arrangement, it will be seen that the only possibility of obtaining a complete 130 metallic circuit between the insulated

5 rail section and the main rails of the track, is by means of the loop circuit under control of the circuit breaker 10, therefore whenever the solenoid controlling the circuit breaker 10, has become deenergized, there is an absolute break across the signal point at block C², by means of the insulated joints above referred to and set forth.

10 The other circuit breakers at the stations control loop circuits around the insulated joints forming train control points, and are the same as above set forth, the circuit breaker 17 through wires 17^a and 17^b and armature 17^c, controlling the stopping point 21; the circuit breaker 18 through the wires 18^a and 18^b and armature 18^c controlling the stopping point 22; the circuit breaker 8 through its wires 8^a and 8^b and armature 8^c controlling the stopping point 23; and the circuit breaker 11, through its wires 11^a and 20 11^b and armature 11^c, controlling the stopping point 24, all located in their respective blocks of the station C².

25 At the stopping point 24, is provided the induction bonds 2, to separate the adjacent blocks, instead of the non-inductive bonds found at the other sections of the track.

30 By tracing the source of supply for controlling the circuit breaker 11, it will be noted that this circuit breaker receives its current by two paths, one running through the armatures of the line relay 8, and the track relay 15, while the other runs through the armatures of the line relay 16 and the 35 track relay 6, thus requiring the opening of two relays, one in each adjacent block before the circuit breaker 11 becomes deenergized.

40 The light signal indicators 12 and 14, at each station are located on each side of the track and are wired to three different colored lights, such for instance as r, y and g, designating red, yellow and green lights.

45 In operation, the signal indicator is read by the motorman on the right side of the track, as designated by the direction in which the car or train is traveling, and besides the two main light signal indicators, there are what are termed two lighting 50 markers 13 and 19, one on each side of the track connected to indicate the condition of the train controlling points, namely 20 and 21 respectively, located a full braking distance from the point of the switch, as for instance one thousand feet or more down the 55 track from the siding. The marker light shows red, when the circuit breaker is open. The above set forth conditions prevail at each station and block, along the right of 60 way of the railroad.

65 Where dangerous curves are located, they are protected by what is termed a repeating circuit, this being illustrated between stations B and C, where an extra line relay 25, is interjected into the line circuit operated

by the track relay 6, in block C², as before described, and controls circuit breaker 27 by the following circuit, transformer 26, wires 26^a and 25^c, armature 25^b, wire 27^c, circuit breaker 27 and wires 27^a and 112 70 back to transformer 26. Circuit breaker 27 controls the signaling point 28 by the wires 27^a and 27^b and armature 27^c and also the extra line relay 29 in block C² is controlled by the track relay 15 in block B², as follows: 75 from transformer 7 at station B, along wires 106 and 116, armature 15^c, point 15^a, wire 29 and wire 29^c of Fig. 3, relay 29, wires 29^a, 112 and 111 back to transformer 7 at station B. 80

This secondary relay 29 controls another circuit supplied from the transformer 26, as follows:—armature 29^c, point 29^a, wire 30^c, circuit breaker 30, wires 30^a and 112, transformer 26, and wires 26^a and 123, thus supplying power for holding the solenoid of the circuit breaker 30 closed, to control the signal point 31, through the wires 30^a and 30^b and armature 30^c, as above described.

85 The local circuit breakers controlled by the relays 25 and 29, also act as repeaters to transmit the signals on to the regular line relays located at the sidings, as line relays 9 at station B, and the line relay 16 at station C, the armatures 25^a and 29^b, accomplishing this function.

90 In this manner it will be obvious that a car located in block B² opens the circuit breaker 30, controlling an approaching car in block C², and in a similar manner, a car 100 in block C², opens the circuit breaker 27 in block B², thus controlling the approaching car in the opposite direction. As these signaling points 28 and 31 are located at a sufficient braking distance that is, approximately 1000 feet from the dangerous point in a curve, the cars will always be protected against accidents.

95 Another condition arising in single track systems, is illustrated in diagram in block C², and it is assumed for instance that this condition be a grade crossing of a steam railroad. In this case, the steam railroad rails 32, are bonded for at least one-half mile in each direction from the crossing or 110 intersection of the two railroads, with insulated joints H, located in the track, as shown, and with this is employed a direct current from gravity batteries 33 and 35, located at a distant point on said steam railroad. A 115 relay 34 is connected with the battery 33 upon one side of the crossing while the relay 36 with battery 35 is on the other side of the crossing. The armatures of these two relays 34 and 36, control local circuits fed 120 from a local transformer 37 through wires 37^a and 37^b, said transformer governing the operation of the circuit breaker 38, having control of the signal point 39, and the circuit breaker 40, having control of the signal 130

point 41, each approximately one thousand feet, or more, from the danger point of the crossing, thus insuring absolute protection against an approaching train on the steam railroad.

When the relay 34 is energized, the armature 34', contacts point 34^a, and the circuit breaker 38 is energized through the transformer 37, wire 37', armature 34', point 34^a, 10 wire 38', circuit breaker 38, wire 38'', point 36^a, armature 36'' and wire 37'. The armature 36' is operated by relay 36, and forms a circuit through the transformer 37, wire 37', armature 36', point 36^a, wire 40', circuit breaker 40, wire 40'', point 34^b, armature 34'' and wire 37''. The circuit breakers 38 and 40 have their usual wires 38^a and 38^b, and 15 40^a and 40^b, respectively, and armatures 38^a and 40^a.

Having described the operation and circuits, with the instruments and their function, the traffic conditions, which might arise on a high speed electric interurban railroad, which it is desired to protect with this 25 system, will be given in detail.

Assuming that a car is located in block B², just leaving station B, and running in the direction of station C, having passed over the induction bond located at the signaling point 24. This car has all signals and stopping points clear in the direction in which it is going, as far as the induction bond, located half-way between stations B and C, at the dangerous point of the curve. 30 It will be evident that that signal current supplied from transformer 3, to rails 4 and 5, in block B², is shunted by the car wheels, thus deenergizing track relay 15 of block B², and this action has set the danger circuit breaker 17, which will stop any car approaching from the direction of the stopping point 21 of block B². The circuit breaker 8 controlling the point 23 at the siding has also been opened, and will prevent any car that has already taken the siding from leaving or going on the main track, until after the moving car which controls this circuit breaker has passed out of the danger zone. Simultaneously with this, 45 the light signal indicator 14 will show red, while the marker indicator 19 for the circuit breaker 17 will also show red. In advance of the train or car, it will be seen that on the opposite side of the dangerous curve, 50 and at a full braking distance from the point of danger, a line relay 29, has been opened, deenergizing the circuit breaker 30, thus placing point 31 in a condition to stop a car approaching from that direction; and the line relay 29 has repeated its signal to line relay 16 at station C, of block C', and in turn deenergizes the circuit breaker 17 of block C', thus throwing the stopping point 21 in block C', open to control an approaching car. Simultaneously

with this, the signal indicator 12 of block C', indicates red and yellow, the green or clear signal having been cut out. By this means, the moving car is protected from any possibility of a car getting into the same block without being halted at one of the signaling points, even though the motorman disregarded the light signal given by the light signal indicator. As the car approaches station C, where it passes over the induction bond 1 between blocks B² and C', the signal and controlling instruments change to the following conditions, viz.,—track relay 15 in block B², again becomes energized, and all the instruments under its control assume their normal position, while the track relay 6, in block C', has been shunted by the car wheels, and in turn controls another set of instruments and opens the track clear for the distance of another block 70 75 80 85 in advance of the moving car.

The track relay 6, controls the line relays 25 and 9, in block B², and in turn the circuit breakers 27 and 10 in the same block, thus controlling the stopping points 28 and 20, respectively, while the signal indicator 14 of block B², shows red and yellow. In advance of the car, the track relay 6, opens the circuit breaker 8 at stopping point 23 on the siding, thus preventing any car that might be standing there from running out on to the main line, which might cause either a head-on collision, or what is termed a "side-swipe" collision to the approaching car.

When the moving car passed from block B² into block C', a circuit breaker 17 in block C' became energized, and simultaneously with that movement, a circuit breaker 10 in block C' became deenergized, thus controlling the stopping point 20 of block C', approximately one thousand feet from the siding, while the signaling indicator 13 of station C', showing the condition of the stopping point 20, is now red, thus insuring protection from collision with an approaching car to the car moving in block C', toward station C, with everything clear in its advance past or beyond the induction bond 2, located at the siding of station C.

Assuming that a car leaves station D, approaching in the direction of station C, and just entering the block D', and having passed the induction bond 2 at station D, the track relay 6, of block D', which is fed from transformer 3, between block C' and block D', and is deenergized, due to the axles of the car shunting the current across the rails 4 and 5, of the block D'. When the track relay 6 becomes deenergized, it immediately opens the armature controlling the circuit breaker 8, at station D siding; the circuit breaker 10 in block D'; line relay 9 in block C', and throws the signal indicator 12 in station D to red, and the marker signal indicator 13 100 105 110 115 120 125 130

in station D also to red. The line relay 9, at station C, in the block C² has been opened, and has controlled the circuit breaker 11 of station C, which has one side of its controlling circuit opened, by the car approaching in block C', but has the other and only remaining source of supply opened at line relay 9 of block C², and thus cut off the last source of supply from said circuit breaker 11, therefore deenergizing it and opening the train controlling circuit at stopping point 24 at station C. The circuit breaker 10 is also controlled by the line relay 9, it having already been opened by the track relay 6, by the car in block C'. The signal indicator 14 of block C², now shows red and yellow, while the green is cut out. The actual condition of the signals and train control points at station C, due to the location 20 of the two cars, one in block C', approaching station C, and the other car in block D', approaching station C, causes the train control points 20 and 24 to be open, so that they will stop any car crossing same. The circuit breaker 8 has become deenergized, opening the car controlling point 23, which thus prevents any car leaving the siding; the signal indicator 12 shows red or a home signal; the marker signal 13 also shows red, while the 30 signal indicator 14 shows red and yellow for distant signal.

In this way, a car in block C', will be stopped when it reaches the train control point 24, the signal indicator 14 having also indicated that there is a car in the distant block between stations C and D, in block D', as shown by the red and yellow light. The marker 13 located at the siding that the train control 20 has opened will also indicate the 40 location of the approaching car, and set a stop for either.

The car therefore at the siding will enter the same, and await the arrival of the approaching car, the car in the siding being held, for it will be impossible for it to leave without being stopped at least several times.

Assuming that the car takes the siding at station C, this action immediately clears up the train control points 24 and 23, and the 50 signal indicator 12 goes to green. It has also cleared all the train control points in station B, and throws the signals there to green or clear.

Should the car in block D' approaching 55 station C, cross the induction bond 1 into block C², the train control points actuated by circuit breakers 8 and 10 of station D will be clear, simultaneously deenergizing the train control point 21 in block D', cutting out one source of supply of the train control point 24. The signals at station D will then show indicator 12 red and yellow, and marker 13 is cut out.

In station C, the track relay 15 of block 65 C² becomes deenergized, thus changing the

train control points so that the stopping point at 20 of block C² has been shifted to 21 at block C', while stopping point 22 at station C at the siding C³, has been opened, thus preventing the car that has just entered the siding from again entering the main line until after the point has been cleared. The signal indicator 14 has changed from yellow and red to red, and the marker 19 indicates red, thus leaving a clear track for the car approaching station C, through block C², until after the car passes the siding at the induction bond 2. At the same time, this car is protected against any car approaching by the train control point 21, or from a "side-swipe" or head-on collision, due to the car standing in the siding by the stopping point 21 in block D'. 70

Should the car pass station C, from block C² in the direction of C', and enter block C', across the insulated joints and induction bond 2, the car controlling point 21 clears in advance of the approaching car, while the stopping point 20 is immediately set, and the controlling points at the siding C are shifted, thus closing points 22 and opening 85 23. In this manner, the car on the siding is released to leave the siding toward block C², but not in the direction of block C', while the signal marker 13 shows the condition of 90 stopping point 20 to the car standing on the siding, as the red light is exhibited, and the signal 14 immediately passes to green or clear, simultaneously with the signal indicator 12 exhibiting red. The track is now 100 clear for passage from block C' to block B², of station B, and at the same time, this is protected against a car leaving the siding by stopping point 23, as well as an approaching car from the rear at stopping point 20, while 105 at station B, the circuit breakers at the stopping points and the signals have been actuated as explained with reference to station C. The stopping point 22 has cleared in advance of the car standing on the siding C³, 110 thus permitting the car to leave the siding in the direction of the station D; and as soon as the car that passed leaves block C', and passes over the insulated joints at the induction bond 1 between blocks B² and C', the 115 stopping point 20 is cleared, and the marker 13 is cut out, giving the car at the siding a clear path to proceed in its regular way.

When leaving the siding, the siding is locked and opens the stopping points both 120 in the rear and advance at the stations or sidings, all as previously explained, thus protecting the car against danger of encountering another car.

If the car which first approached station 125 C instead of entering the siding remained upon the main line in block C', the signal lights would indicate plainly where the car was located, that is approaching the siding from the opposite direction, and if the mo- 130

5 torman observed the light signals, he need
not be automatically stopped, but if on the
contrary he failed to observe the signals, the
car is automatically stopped, and held there
upon the main track, at or near the siding.
10 This opens the stopping point 20, which is
located at braking distance from the siding,
so that the approaching car will itself be
automatically stopped between stopping
points 24 and 20, thus protecting both cars
from head-on or rear end collisions.

15 In case, one of two approaching cars moving
toward the switch at station C', should
pass over the stopping point 21 while the
other passes from block D' to block C',
crossing the insulated joints at the induction
bond 1, the car in block C', would not receive
the signal at stopping point 21 in time to
stop, but the circuit breaker 11 at station C,
20 being controlled by both cars, is deenergized,
thus opening the stopping point 24 at station
C, to stop the car in block C'; and it in
turn controls stopping point 20 in block C',
to stop a car coming from that direction,
25 thus protecting both cars, even though they
may be approaching at high speed, they having
a full braking distance in which to be
stopped automatically.

30 At station B, there is located what is
termed an open ended switch, where in such
cases the circuit breaker 8, will be controlled
by the track relays of both blocks,
namely blocks B' and B''. In this way, a car
approaching the siding from either direction
35 will hold any car that has taken the
siding against leaving, and thus prevent an
accident. The car is held in the switch until
the approaching car has passed into the adjacent
block. In this instance, it will be
40 noted that the induction bond 2, which separates
blocks B' and B'', is moved about one
car's length from the point of the switch,
thus enabling a car to approach and take a
siding without being endangered by an
45 approaching car.

50 In other words, assuming that a car approaches station B, from station A, through
block B', it will be held at car controlling
points 20 and 23 in the stopping position,
which will avoid any danger from an
approaching car or from a car in the siding;
55 and at the same time, in case a car is approaching from the opposite direction, it
will hold the car near the siding in check,
and avoid an accident from that direction.

60 There is another traffic condition that may
arise, where two cars approaching each
other leave station B and station C, simultaneously, and cross the insulated section at
the induction bonds 2, in each block. It
65 might be possible with this system for them
not to stop one another at the stopping
points 24 of each block, but they still are
secure and safe, for the reason that the car in
block B'', in crossing section 24, sets the car

controlling point 21, in block C', while the
car traveling in block C', simultaneously
sets the car controlling point 20 in block B'',
and the corresponding light signals. This
will stop both cars before they have gone
over one thousand feet from their siding,
and thereby avoid the possibility of an accident. 70

75 Wherever there is a dangerous curve
along the right of way, it is protected as
illustrated by the repeating signals on each
side of the danger point, as indicated by
line relays 25 and 29, controlling the stop-
ping points 28 and 31, as previously de-
scribed, thus avoiding collision in these 80
places. Grade crossings are protected in a
similar manner by wiring the track of the
crossing railroad in such a manner that it
will protect and control any approaching
car on the electric railroad. This is fully 85
illustrated in block C'.

90 By tracing out the various circuits, it is
shown that one car can readily determine
from the signals when approaching the siding,
the exact location of any car within
two blocks of said siding, thus informing
each motorman, of the exact condition of
the track in front and in the rear, and also
the direction in which his neighbor is travel-
ing. At the same time, in the event of a 95
disregard of the signals, the automatic stop
mechanisms located at the various stopping
points will be placed in a position to stop
the car.

100 Should cars leave station B, and station D, simultaneously, and approach station C,
at a high rate of speed, the insulated joint
1 having been crossed, between blocks B''
and C', and also between blocks C' and D',
both moving toward station C, it will be 105
seen that the car in block C', throws con-
trolling point 20 into stopping position,
and the car in blocks C' throws controlling
points 21 open, and both then hold stop-
ping point 24 open. In this manner both 110
cars will be automatically stopped as they
pass over controlling points 20 and 21, and
will therefore be brought to a standstill be-
fore they reach station C, at a siding, which
will enable them to pass safely. 115

120 From the foregoing description of the
diagram and the operation of this safety
signal system, it is evident that its greatest
value is in having the track circuits so wired
and connected by means of the insulated
rail sections, which are either looped around
by inductive or non-inductive bonds, and
placed under the control of a circuit breaker,
which is operated by a distant signal cir-
cuit, so that when a car is properly wired
and equipped with the instruments for re-
ceiving said indications, as set forth in ap-
plication Serial No. 555,804, the car or train
will not only receive the signal in the cab
thereof, but is placed at all times under au- 130

tomatic control, due to the arrangement or disposition of the track signal circuit, and yet is able at the same time to give signals in the usual form. By this invention absolute protection is assured, even where the signals have been disregarded, either by carelessness or the inability of the operator to control his car or train.

What is claimed, is:—

- 10 1. A railway signal system comprising: a track divided into blocks, a circuit for each block, train controlling means in said track, and means controlled jointly by the two block circuits on opposite sides of said track controlling means to control the operation of said train controlling means.
- 15 2. A railway signal system comprising: a track divided into blocks, a circuit for each block, an insulated train controlling section in said track, a connection between the insulated section and the track outside the section, and means controlled by the con-
- 20

current disturbance of two block circuits on opposite sides of said train controlling section to control the connection between said section and the track outside the section.

3. A railway signal system comprising: a main track divided into blocks, a circuit for each block, a branch track connected to said main track within one of said blocks, a train controlling means in said main track between the point of connection of said branch track with said main track and an adjoining block, and means controlled jointly by the circuits of said adjoining blocks to control said train controlling means.

In testimony that I claim the foregoing as my own, I have hereto affixed my signature in the presence of two witnesses.

GUY P. THURBER.

Witnesses:

JOHN F. SWEENEY,
PAUL ALAND.
